UNITED STATES PATENT OFFICE.

CARL H. BISSELL, OF SYRACUSE, NEW YORK, ASSIGNOR TO ELECTRIC OUTLET COMPANY, INC., OF NEW YORK, N. Y., A CORPORATION OF NEW YORK

OUTLET BOX.

Application filed January 19, 1923. Serial No. 613,614.

To all whom it may concern:

Be it known that I, CARL H. BISSELL, a citizen of the United States, residing in the city of Syracuse, in the State of New York, have invented certain new and useful Improvements in Outlet Boxes, of which the following is a specification, reference being had to the accompanying drawings, forming a part hereof.

10 This invention relates generally to the type of outlet box shown in the Vibber Patent No. 932,196, in which clamping elements on the front and rear faces of a wall are secured together to afford a staple support for an outlet box. In employing this method of installation it is necessary to introduce the back clamping element through the opening cut in the wall and then subsequently unite the front clamping element 15 with it through the securing devices. The present invention has for its principal object to associate with the back clamping member suitable means for retaining it in place until such time as the front clamping member 20 is secured thereto. More particularly, the invention seeks to provide, as an improved article of manufacture, a back clamping member for the purpose described which shall have formed as an integral part thereof 25 the means for retaining the member in position on the reverse face of the wall until such time as the front clamping member is permanently secured thereto. In the preferred embodiment of the invention the 30 back member carries one or more flexible tangs which may be bent over to engage the wall along the edge of the opening.

The invention will be described with reference to the embodiment illustrated in the 35 accompanying drawings wherein:

Figure 1 is a view in elevation of the rear side of the improved clamping member.

Figure 2 is a view in perspective of a portion thereof showing one of the flexible 40 tangs.

Figure 3 is a view in vertical section through the clamping element secured in an opening in a lath and plaster wall by the flexible tangs.

50 Figure 4 is a view in perspective of a portion of a front clamping member.

It will be understood that the improved clamping member *a* may be of any form and dimensions but as illustrated herein is 55 of generally rectangular form and including

not only the flanged section *a'* to bear against the rear side of the laths but also an inner peripheral flange *a*² of the same configuration as the opening. In installing a box such as *b* which is to be supported by 60 clamping members such as the back clamping member *a* and a front clamping member *c* it is desirable, after the opening is cut in the wall, to pass the back clamping member *a* through the opening and hold it in place 65 until the front clamping member *c* is secured thereto as through securing screws *d* passing through the front member *c* and taking into openings *a*³ provided therefor in the flat flange *a'*. When the back clamping member *a* is thus supported in the opening 70 the wires may be fished and drawn out through the opening in the clamping member for introduction into the box *b* before the box is permanently mounted. The peripheral flange *a*² of the clamping member *a* facilitates fishing of the wires since it forms a smooth facing for the opening in the wall. Heretofore, no means have been proposed for securing the back clamping 75 member in place and the expediency has been resorted to of holding it by means of one or more of the retaining screws *d*. This is somewhat inconvenient and such an expedient does not maintain the back 80 clamping member in proper relation to the opening during fishing of the wires without special attention on the part of the workman. By the improved construction it is proposed to associate with the back clamping member *a* means by which it may be 85 held in place until such time as the retaining screws *d* are finally passed between the front clamping member *c* and the back clamping flange *a'*. Such means in the preferred form consist of flexible tangs *a*⁴ carried integrally with the peripheral flange *a*² and disposed in any number and in any 90 positions found to be necessary or most effective. In the illustrated form two such tangs are shown as disposed at the top and bottom of the peripheral flange *a*² and centrally thereof. When the back clamping is properly positioned the workman may 95 bend the tangs *a*⁴ over the edge of the laths or other wall material indicated at *e* and the tangs will embrace the wall material with sufficient positiveness to hold the back clamp *a* in position during the fishing of 100 the wires and until such time as the front 105 clamp *c* is secured. The tangs *a*⁴ are 110

2
clamping member *c* is permanently secured thereto by the through screws *d*. If desirable, the front flange member *c* may have formed therein openings *c'* alined with the tangs *a*⁴, respectively, so as to receive them without interference.

The invention is not limited to the precise character of the back clamping element nor the front clamping element so long as elements are provided which will co-operate for the support of an outlet box in accordance with the principle described by Vibber Patent No. 932,196. For that reason, it is immaterial whether the front clamping flange *c* is carried with the box *b* or whether the box is independent thereof. Further, the invention is not to be limited to the provision of integral tangs *a*⁴ on the back clamping member *a* although this appears to be the cheapest and most effective construction.

What I claim is:

1. As an article of manufacture, a back clamping plate for the purpose described having means for co-operation with the wall on which the plate is mounted for tempo-

rary supporting the plate, said plate also having means for co-operation with permanent retaining devices.

2. As an article of manufacture a back clamping plate for the purpose described having formed integrally therewith adjacent the peripheral opening therein means for co-operation with the wall on which the plate is supported to support the plate temporarily.

3. A back clamping plate for the purpose described having formed integrally therewith flexible means for co-operation with the wall on which the plate is supported, to retain the plate temporarily in fixed relation to the wall.

4. In combination, front and back clamping plates for the support of an outlet box, means for permanently uniting said clamping plates and independent means carried with the back plate to support it temporarily in fixed relation to the wall.

This specification signed this 20th day of December A. D. 1922.

CARL H. BISSELL.
